Primary Examiner — Garth Rademaker*Assistant Examiner* — Katie S Mroczka(74) *Attorney, Agent, or Firm* — Perkins Coie LLP(57) **CLAIM**

We claim the ornamental design for an animal chew, as shown and described.

DESCRIPTION

FIG. 1 is a front isometric view of an animal chew showing our new design.

FIG. 2 is a front elevation view thereof; the back elevation view is a mirror image of the front elevation view.

FIG. 3 is a left side elevation view thereof; the right side elevation view is a mirror image of the left side elevation view; and,

FIG. 4 is a top plan view thereof; the bottom plan view is a mirror image of the top plan view.

1 Claim, 4 Drawing Sheets(56)
